UNITED STATES PATENT OFFICE.

WILLIAM C. YOUNG AND JOHNSTON McMAHON, OF BUFFALO,
NEW YORK.

TROLLEY-CATCHER.

SPECIFICATION forming part of Letters Patent No. 752,139, dated February 16, 1904.

Application filed June 1, 1903. Serial No. 159,463. (No model.)

To all whom it may concern:

Be it known that we, WILLIAM C. YOUNG and JOHNSTON McMAHON, citizens of the United States, and residents of Buffalo, in the county 5 of Erie and State of New York, have invented new and useful Improvements in Trolley-Catchers, of which the following is a specification.

This invention relates to trolley-catchers 10 which operate to pull the trolley downwardly below its normal position when the same upon leaving the trolley-wire moves upwardly above its normal position, thereby preventing the trolley from engaging with the overhead supports and injuring the same.

The object of this invention is to produce 15 a trolley-catcher of this character which is reliable in operation and simple and durable in construction and which can be easily set or put in operative condition.

In the accompanying drawings, consisting 20 of two sheets, Figure 1 is a fragmentary side elevation of a car equipped with our improved trolley-catcher. Fig. 2 is a fragmentary vertical section of the same, on an enlarged scale, showing the position of the parts when the catcher is ready for use. Fig. 3 is a similar view taken at right angles to Fig. 2 and showing the position of the parts when 25 the catcher has pulled the trolley downwardly. Fig. 4 is a section similar to Fig. 2, showing a slight modification in the construction of the trolley-catcher. Figs. 5 and 6 are horizontal sections in line 5 6, Fig. 2, looking in 30 opposite directions. Figs. 7 and 8 are horizontal sections in the correspondingly-numbered lines in Fig. 2. Fig. 9 is a fragmentary vertical section of the bracket which supports the lower end of the standard of the 35 trolley-catcher. Fig. 10 is a top plan view of the guide on the roof of the car which controls the position of the trolley-rope between the trolley and the catcher.

Similar letters of reference indicate corresponding parts throughout the several views.

A represents an upright standard, which is preferably of cylindrical or tubular form. This standard is seated at its lower end in a socket or seat b, formed in a bracket B, se- 40 cured to the bumper c or lower part of the

car C, while its upper part is secured to the vestibule or other available part of the car by means of a loop or band d, embracing the standard and secured at its ends to the car. The lower end of the standard is detachably 55 secured in its socket, preferably by means of a cross-pin e, extending diametrically through the standard and engaging its ends which project from opposite sides of the standard with undercut slots d', formed in the sides of 60 the socket. For the purpose of securing the standard in the socket of the bracket the same is lowered with the ends of its pins in the vertical parts of the slots d' and then turned horizontally, so that these ends engage the 65 horizontal parts of said slots, whereby the standard is locked against vertical movement. This means of detachably connecting the lower end of the standard with the car enables the 70 same catcher to be employed at either end of the car by providing a bracket for receiving the standard at both ends of the car. At its upper end the standard is provided with a top plate or cap F, which is connected with the upper end of the standard by a plurality 75 of vertical arms f, forming side openings f' between said arms, which afford access to the space between the upper end of the standard and its top plate.

G represents a main spring, which is operatively connected with the rope g of the trolley-pole H and which upon contracting exerts a downward pull upon the trolley for depressing the same below its normal position. This main spring preferably has the form of a 80 coil, which is arranged within the standard and secured at its lower end to the cross-pin e. At its upper end the main spring is secured to a center piece i, which has a vertical coupling-bolt l passing centrally through the same. 85

J represents a carrier or yoke arranged transversely above the coupling-bolt and connected centrally on its lower side with the latter by means of a link j' or otherwise. Centrally on its upper side the yoke is provided 90 with a pulley j'. The trolley-rope g passes around this pulley and is secured at one end to an eye f' on the under side of the top plate, while its other end passes upwardly through an opening f'' in said top plate. Undue wear 95

upon the trolley-rope is prevented as it passes back and forth through the opening f^2 by means of guide-rollers h , which are mounted on the under side of the top plate adjacent to its opening and which receive the trolley-rope between them.

L represent two latches, whereby the main spring is held in its distended or expanded condition preparatory to pulling the trolley downwardly. These latches are pivoted at opposite ends of the yoke, so as to turn in a vertical plane by means of pins l , and each latch is provided on its outer side with a downwardly-projecting shoulder m , a guide-tail m' projecting below said shoulder and a finger-piece m'' projecting above said shoulder. In the normal or operative position of the latches their shoulders are in their outermost position and engage with the annular shoulder n , formed by the upper edge of the tubular standard. In the inoperative position of the latches their shoulders are in their innermost position and clear the shoulder on the standard. When free, the latches are moved into their inoperative position by means of a spring o , which preferably connects the same below their pivots.

For the purpose of setting the trolley-catcher preparatory to running the car the trolley-rope is first pulled upwardly through the top plate until the finger-pieces of the latches are opposite the side openings of the standard and their shoulders are in position to be engaged with the shoulder of the standard. During this movement of the latches and the trolley-rope the main spring is distended or expanded, the power thus stored up in the same being subsequently utilized for pulling the trolley below its normal position. While the latches are in an elevated position the attendant, by reaching through the side openings f^2 presses the finger-pieces of the latches toward each other, so as to carry the shoulders of the same outwardly over the shoulder of the standard. At the same time the trolley-rope is slackened, causing the main spring to pull the latches downwardly while in their projected position until their shoulders engage with that of the standard, as shown in Fig. 2. During the normal operation of the trolley the latches remain in engagement with the standard and hold the main spring in a distended condition, notwithstanding that the spring o tends constantly to turn the latches inwardly for retracting their shoulders from the standard. This is due to the fact that the pull of the main spring far exceeds the pull of the retracting-spring o , causing the latches to be held frictionally in engagement with the standard and overcoming the effect of the retracting-spring o . The parts remain in this position as long as the trolley remains on the overhead wire h and the extent of its vertical movement is within normal limits. When the trolley leaves the wire and moves above

the normal limit, the same exerts a pull or jerk on the rope, which has the effect of slightly raising the yoke, together with the latches and main spring connected therewith. The instant said parts are thus raised the latches are released from frictional contact with the standard and are turned by the spring o in the direction for retracting their shoulders inwardly out of engagement from that of the standard. When this occurs, the main spring is released, permitting the same to contract, owing to its resilience, into the position shown in Fig. 3. While the main spring moves into its contracted position, the pulley j' pulls the trolley-rope downwardly and carries the trolley connected therewith below its normal position.

In pressing the finger-pieces of the latches together the movement of the latches in this direction is limited by co-operating stop shoulders p , formed on the latches, and the yoke, which are so arranged that the latches are stopped when their shoulders are arranged above the shoulder of the standard, thereby enabling the catcher to be easily set without requiring special care. The latches are centered in the standard for causing their shoulders to properly engage the shoulder of the standard by means of the tails engaging with the inner side of the standard. The outer sides q of these tails are curved downwardly and inwardly, so that upon lowering the catches while in a projected position the catches are guided so that their shoulders properly engage that of the standard. It will be observed that when once the latches are disengaged from the standard the main spring is positively released and is certain to act, because the latches are retained in their retracted position until they are again restored by hand into working position.

In order to prevent the main spring from being stretched too far and the parts connected therewith from being raised too high, a stop device is provided which limits this movement. This stop device preferably consists of a flexible chain or rope r , arranged within the main spring and connected at its lower end to the cross-pin e and at its upper end to the coupling-bolt I . This stop-rope is of such length that it is somewhat slack when the latches are in engagement with the shoulder of the standard in the operative condition of the catcher. When the trolley-rope pulls the yoke and connecting parts upwardly, its movement is arrested when the slack in the stop-rope has been exhausted. By this means the pull of the trolley-rope is prevented from drawing the parts so high as to draw the latches up against the top plate, and undue straining of the main spring is also prevented. In order to prevent a sudden jar upon the catcher when the trolley leaves the wire, a retarding device is provided which checks the upward movement of the parts within the

standard. This retarding device preferably consists of a cup-shaped or dished piston *s*, of leather or other flexible material, secured centrally to the upper end of the main spring, with its concave side facing upwardly and engaging its periphery with the interior or bore of the standard. The piston is preferably secured in place between upper and lower washers *t t'*, which are firmly turned against opposite sides of the central part of the piston by means of the coupling-bolt *I*. During the upward movement of the movable parts of the catcher, due to the pull of the trolley-rope, the piston, owing to its dished formation, tends to spread and grip against the inner side of the standard and retard its upward movement and the parts connected therewith. During the downward movement of the piston its marginal portion moves freely downward through the standard, owing to its dished shape, thereby offering but slight resistance to the main spring and enabling practically the full power of the latter to be expended in pulling the trolley-pole downwardly. This retarding-piston does not prevent the attendant from again raising the main spring and resetting the trolley-catcher, because the same can be pulled slowly upward with comparative ease, but affords considerable resistance when pulled up suddenly.

Upon the end of the car-roof adjacent to the trolley-rope the same is provided with a guide which controls the position of the intermediate part of the trolley-rope. This guide, as shown in Fig. 10, consists of two spring-arms *u*, secured side by side at their inner ends to the edge of the car-roof, forming an eye between them. The free ends of the spring-arms are curved to permit of easily springing the trolley-rope into and out of the space between the eyes. For the purpose of reducing the friction in the rope-guide the latter is provided with a roller *v*, which is pivoted transversely between the inner ends of the spring-arms. As the trolley rises and falls its rope runs on the rear side of the roller *v*, and undue wear of the same or the guide is thus avoided. In the construction of the trolley-catcher shown in Fig. 4 the top plate is omitted and the trolley-rope is attached directly to the yoke. Furthermore, the retarding device is omitted and the main spring and stop-rope are connected to the link on the lower side of the yoke.

We claim as our invention—

1. A trolley-catcher comprising a standard having a shoulder, a spring for retracting the trolley secured at its fixed end to the standard, a detent device connected with the movable end of the spring and constructed to engage said shoulder for holding the spring in a strained condition, and means operating to disengage the detent from said shoulder independently of the pull which is exerted by the trolley, substantially as set forth. 65
2. A trolley-catcher comprising a standard provided with a shoulder, a main spring for pulling the trolley downwardly secured at one end to said standard, a latch connected with the other end of said spring and constructed to engage said shoulder in the normal operation of the trolley, and a retracting-spring which constantly tends to withdraw said latch from said shoulder independently of the pull of the trolley, substantially as set forth. 70
3. A trolley-catcher comprising a standard provided at its upper end with a shoulder, a main spring for pulling the trolley downwardly secured at its lower end to the lower end of said standard, a yoke secured to the upper end of the main spring and receiving the pull of the trolley, a latch pivoted on the yoke and constructed to engage said shoulder, and a retracting-spring for disengaging the latch from said shoulder operating independently of the pull of the trolley, substantially as set forth. 75
4. A trolley-catcher comprising a standard provided at its upper end with a shoulder, a main spring for pulling the trolley downwardly secured at its lower end to the lower end of said standard, a yoke secured to the upper end of the main spring and receiving the pull of the trolley, a latch pivoted on said yoke and provided with a shoulder adapted to engage with the shoulder of said standard, said latch being free to swing inwardly but its outward movement being limited by co-operating stop-faces on the latch and yoke, and a spring for retracting said latch into an inoperative position, substantially as set forth. 80
5. A trolley-catcher comprising a standard provided at its upper end with a shoulder, a main spring for pulling the trolley downwardly secured at its lower end to the lower end of said standard, a yoke secured to the upper end of the main spring and receiving the pull of the trolley, a latch pivoted on the yoke and provided with a shoulder co-operating with the shoulder of the standard and with a finger-piece, and a spring for retracting said latch, substantially as set forth. 85
6. A trolley-catcher comprising a standard provided at its upper end with a shoulder, a main spring for pulling the trolley downwardly secured at its lower end to the lower end of said standard, a yoke secured to the upper end of the main spring and receiving the pull of the trolley, a latch pivoted on the yoke and provided with a shoulder co-operating with the shoulder of the standard, a downwardly-projecting guide-tail and an upwardly-projecting finger-piece, and a spring for retracting the latch, substantially as set forth. 90
7. A trolley-catcher comprising a standard provided at its upper end with a shoulder, a main spring for pulling the trolley downwardly secured at its lower end to the lower end of said standard, a yoke secured to the upper end of the main spring and receiving the 95

- pull of the trolley, a latch pivoted on the yoke and provided with a shoulder coöperating with the shoulder of the standard, a downwardly-projecting tail having a curved guide-face on its outer side and an upwardly-projecting finger-piece, and a spring for retracting the latch, substantially as set forth.
8. A trolley-catcher comprising a standard having a shoulder at its upper end, a main spring for retracting the trolley secured at its lower end to the lower end of the standard, a yoke receiving the pull of the trolley and connected centrally with the upper end of the main spring, latches pivoted at opposite ends of the yoke and each constructed to engage said shoulder, and means operating to disengage the detent from said shoulder independently of the pull of the trolley, substantially as set forth.
9. A trolley-catcher comprising a standard having a shoulder at its upper end, a main spring for retracting the trolley secured at its lower end to the lower end of the standard, a yoke receiving the pull of the trolley and connected centrally with the upper end of the main spring, latches pivoted at opposite ends of the yoke and each constructed to engage said shoulder, and a spring for disengaging said latches from said shoulder operating independently of the pull of the trolley, substantially as set forth.
10. A trolley-catcher comprising a standard having a shoulder at its upper end, a main spring for retracting the trolley secured at its lower end to the lower end of the standard, a yoke which receives the pull of the trolley connected centrally to the upper end of the main spring, latches pivoted at opposite ends of the yoke and each provided with a shoulder constructed to engage the shoulder of the standard, a downwardly-projecting guide-tail and an upwardly-projecting finger-piece, and a spring connecting the tails of both latches and operating to disengage the latches from the shoulder of the standard, substantially as set forth.
11. A trolley-catcher comprising a tubular standard having a shoulder and side openings at its upper end, a main spring for retracting the trolley arranged in the standard and connected thereto at its lower end, a yoke receiving the pull of the trolley secured to the upper end of the main spring, latches for engaging a shoulder on the upper end of the standard mounted on the yoke and provided with finger-pieces normally arranged opposite the openings in the standard, and a spring for retracting said latches into an inoperative position, and operating independently of the pull of the trolley, substantially as set forth.
12. A trolley-catcher comprising a standard, a main spring for retracting the trolley secured at its lower end to the standard and operatively connected at its upper end with the trolley - rope, a latch for holding the main

spring in a distended condition, and a stop device for limiting the distending movement of said spring, substantially as set forth.

13. A trolley-catcher comprising a standard, a main spring for retracting the trolley secured at its lower end to the standard and operatively connected at its upper end with the trolley - rope, a latch for holding the main spring in a distended condition, and a slack stop-rope connecting the upper end of the spring with the lower end of the standard for limiting the distention of the spring, substantially as set forth.

14. A trolley-catcher comprising a standard, a pin secured diametrically to the lower end of the standard and having its ends projecting from opposite sides thereof, and a socket receiving the lower end of the standard and provided in its side with bayonet or undercut slots which receive the ends of said pin, substantially as set forth.

15. A trolley-catcher comprising a tubular standard, a main spring for retracting the trolley arranged within the standard and secured thereto at its lower end while its upper end is operatively connected with the trolley, a latch connected with the upper end of said spring and constructed to engage with the standard for holding the spring in a distended condition, and a device for retarding the distending movement of the spring, substantially as set forth.

16. A trolley-catcher, comprising a tubular standard, a main spring for retracting the trolley arranged within the standard and secured thereto at its lower end while its upper end is operatively connected with the trolley, a latch connected with the upper end of said spring and constructed to engage with the standard for holding the spring in a distended condition, and a retarding device connected with the upper end of the spring and frictionally engaging with the inner side of said standard, substantially as set forth.

17. A trolley-catcher, comprising a tubular standard, a main spring for retracting the trolley arranged within the standard and secured thereto at its lower end while its upper end is operatively connected with the trolley, a latch connected with the upper end of said spring and constructed to engage with the standard for holding the spring in a distended condition, and means for retarding the distending movement of the spring consisting of an upwardly-dished cup of flexible material secured to the upper end of the spring and engaging its periphery with the interior of the standard, substantially as set forth.
